United States Patent Office.

LYMAN M. SEVERANCE, OF DIXON, ILLINOIS.

Letters Patent No. 94,517, dated September 7, 1869.

IMPROVEMENT IN PLATFORM-SCALES.

The Schedule referred to in these Letters Patent and making part of the same.

To all whom it may concern:

Be it known that I, LYMAN M. SEVERANCE, of Dixon, in the county of Lee, and State of Illinois, have invented a new and useful Improvement in Platform-Scales; and I do hereby declare the following to be a full, clear, and exact description of the same, reference being had to the accompanying drawings, and the letters and figures marked thereon, which form a part of this specification, and in which—

Figure 1 represents a side elevation of my invention.

The nature of my invention consists in the special connections and bearings, hereafter fully described, connecting the horizontal levers beneath the platform of the scales with the rod attached to the scale-beam, whereby each lever acts entirely independent of the other levers upon the rod.

To enable those skilled in the art to understand how to manufacture and use my invention, I will proceed to describe the same with particularity.

The same letters of reference refer to the corresponding parts in the different figures.

In the annexed drawings—

A A and B B represent the four horizontal levers usually arranged beneath a certain well-known class or kind of platform-scales.

For a full description of the construction and arrangement of said levers, and the frame and platform of the scales I use, I refer to the Letters Patent issued to me for an "improvement in platform-scales," on the 6th day of August, A. D. 1867. I, however, prefer to arrange the levers A A in the same plane, or one

as high as the other, and also the same with reference to B B; but I arrange the bearing of one of the levers A above the bearing of the other by attaching the splice or nose-piece D of one higher than the other.

These levers have bearings upon the connecting-pieces C, which consist of a point resting in a socket, as clearly indicated in the drawings by the dotted lines. These connecting-pieces are connected with the rod E by having bearings at F, which also consists of a point resting in a socket, as clearly indicated in the drawings by the dotted lines. These bearings, connecting the pieces C with the rod E, are upon arms or projections rigidly attached to the rod.

This kind of connection between the levers and the rod E enables me to have the ends of the levers directly under each other, and, at the same time, connect them with the rod, so that each one will act thereon entirely independent of all the other levers. It also causes the scales to weigh correctly even when the platform is not level.

Having thus fully described the construction and operation of my invention,

What I claim, and desire to secure by Letters Patent, is—

The combination of the connecting-pieces C, levers A and B, and rod E, when constructed and arranged substantially as and for the purposes described and set forth.

LYMAN M. SEVERANCE.
